[57] **CLAIM**

The ornamental design for a nestable latch operating handle and housing unit, as shown and described.

DESCRIPTION

FIG. 1 is a perspective view of a nestable latch operating handle and housing unit embodying the design of the present invention, with the handle being shown in an extended position relative to the housing;

FIG. 2 is a top plan view thereof;

FIG. 3 is a side elevational view thereof;

FIG. 4 and 5 are end elevational views thereof;

FIG. 6 is a bottom plan view thereof;

FIG. 7 is a perspective view thereof with the handle nested relative to the housing; and

FIG. 8 is a top plan view thereof with the handle nested. Those portions of the drawings in FIGS. 1, 3, 4, 5, 6 and 7 that are shown in broken lines are illustrated for environmental association purposes only, and are not a part of the claimed design.
